UNITED STATES PATENT OFFICE.

WILSON E. PORTER, OF NEW HAVEN, CONNECTICUT, ASSIGNOR TO NEW HAVEN CLOCK CO., OF NEW HAVEN, CONNECTICUT, A CORPORATION.

KEYLESS AUTOMOBILE-CLOCK.

1,100,443.

Specification of Letters Patent. Patented June 16, 1914.

Application filed October 27, 1913. Serial No. 797,540.

To all whom it may concern:

Be it known that I, WILSON E. PORTER, a citizen of the United States, residing at New Haven, in the county of New Haven and State of Connecticut, have invented a new and useful Improvement in Keyless Automobile-Clocks; and I do hereby declare the following, when taken in connection with the accompanying drawings and the characters of reference marked thereon, to be a full, clear, and exact description of the same, and which said drawings constitute part of this application, and represent, in—

Figure 1 a view in front elevation of a keyless automobile clock constructed in accordance with my invention. Fig. 2 a view of the clock in central, vertical, longitudinal section, barring the parts of the movement proper, which are shown in side elevation. Fig. 3 a view in front elevation of the clock with its crystal, bezel, dial, dial-back, independently organized time-movement and the two outer spacing-rings removed to show the winding-and-setting wheels in their normal or winding positions with relation to the internal winding-and-setting gear. Fig. 4 a corresponding view with the winding-and-setting wheels shifted into their setting positions, and with portions of the mounting-flange of the clock-case broken away. Fig. 5 a broken view in inside elevation of the front movement-plate of the power-movement showing, in broken lines, the oscillating gear-carrying yoke and the spring for operating the same. Fig. 6 a detached perspective view of the lever employed for operating the said yoke. Fig. 7 a detached, broken detail view, showing the universal pillar upon which the driven wheel is mounted, together with the several movement-plates and the spacing sleeves interposed between them and the position of the operating-lever.

My invention relates to an improvement in keyless automobile clocks of the type shown in my pending application No. 755,539 filed March 19, 1913, the object being to adapt the clock of that application to be mounted in automobiles having in place of the ordinary dashboard, an over-hanging hood known as a "cowl-board."

With these ends in view, my invention consists in a keyless automobile clock having certain details of construction and combina-

tions of parts as will be hereinafter described and pointed out in the claim.

In carrying out my present invention, the cylindrical clock-case body 2 is provided at its forward end with a relatively wide, annular mounting-flange 3 located in a plane at a right angle to the axis of the clock and furnished with screw-holes 4 by means of which the flange is screwed directly to the cowl-board (not shown) which is furnished with a circular opening large enough to have the case 2 set into it, whereby the clock is suspended, as it were, by the flange 3 in the cowl-board instead of being attached in the ordinary manner by its rear end to the front of a dashboard.

The body 2 of the case being located back of the cowl-board when my improved clock is installed as described, special means must be provided for manually shifting the winding-and-setting mechanism of the clock from its winding to its setting adjustment, and vice versa, my improved clock belonging to that class of keyless clocks in which the shifting of the mechanism from winding to setting, and vice versa, is not effected by laterally moving the rotary winding and setting ring. For this purpose, I form the flange 3 at a point centrally below the clock-dial 5, with a segmental slot 6 receiving the stem 7 of a knurled button 8 standing just in front of the flange, this button being mounted in the bent outer end of an operating-lever 9 which extends through a slot 10 in the lower face of the case 2. The inner end of this lever is cut away to form a fork 11 adapting it to fit over and rock upon a spacing-sleeve 12 mounted upon the universal pillar 13, and interposed between the rear movement-plate 14 of the power-train and the forward movement-plate 15 thereof, as shown in Fig. 7. A sleeve 16 mounted upon the sleeve 12 and shorter than the same by the thickness of the yoke 11, is provided for preventing the lateral displacement thereof upon the sleeve 12, the yoke 16 being held between the forward edge of the sleeve 16 and the rear face of the plate 15, as shown in Fig. 7.

The operating-lever 9 is formed with a cam surface 17 engaging with the adjacent edge of the rearwardly turned arm 18 of an oscillating gear-carrying yoke 19 provided with a fixed hollow stud 20 furnished at its

forward end with a relatively thick circular spacing shoulder 21. The said stud provides a bearing for the driven wheel 22 which rotates loosely upon it and which is 5 interposed between the outer face of the yoke and the inner face of the spacing-shoulder 21 of the stud 20 which latter turns freely upon a short spacing-sleeve 23 mounted directly upon the universal pillar 10 18 and interposed between the front face of the front-movement plate 15 of the power-train and the inner face of the rear movement-plate 24 of the independently organized time-train having a corresponding 15 front movement-plate 25. The yoke 19 is also provided with a solid stud 26 carrying an oscillating winding-and-setting driven wheel 27 constantly in mesh with the driven wheel 22 and carrying upon its outer face 20 an oscillating winding-and-setting pinion 28 normally in mesh with the removable main winding wheel 29 which has a square opening for the reception of the projecting outer end of the winding-arbor 30, the said 25 wheel 29 being supported in position for engagement with the pinion 28 by means of a removable washer 31 resting upon the front face of the front movement-plate 15 of the power-train as shown in Fig. 2.

30 The yoke 19 is normally held in its winding position in which it is shown in Fig. 3, by a spring 32 fixed to the rear face of the front movement-plate 15 of the power-train and engaging with a pin 33 carried by the 35 yoke 19 and projecting through a segmental slot 34 in the said plate 15. To limit the swinging movement of the yoke 19, I mount in it a stop-pin 35 which travels in a slot 36 in the plate 15, the said pin engaging 40 with the ends of the slot, whereby the oscillating movement of the yoke 19 is limited. The winding arbor 30 carries an ordinary spring barrel 37 furnished at its forward end with a main wheel 38, the arbor being 45 furnished at its projecting rear end with a winding ratchet 39 engaged by a spring pawl 40.

The driven wheel 22 is constantly in mesh with the teeth 41 of the winding-and-setting 50 gear 42 which has rotary bearing upon the edges of the rear and front movement-plates 24 and 25 of the independently organized, removable time-train, whereby the said gear is centered with relation to the said movement. For preventing the lateral movement of the gear 42, its teeth 41 are interposed and ride between two spacing-rings 43 and 44, shown in Fig. 6, and particularly described in my before mentioned pending 55 application. A bent spacing-ring 45 interposed between the spacing-ring 44 and the rear face of the rear movement-plate 24 of the removable time-movement, is employed to prevent the forward movement of the gear 60 42. The removable time-movement con-

tained between the plates 24 and 25 is constructed and utilized in accordance with the instructions of my prior application referred to, and need not be described here.

Upon the projecting forward end of the 70 gear 42, I mount a bezel-carrying ring 46 formed upon its rear edge with a flange 47 fitting over the forward edge of the clock-case body 2. The forward edge of the bezel-carrying ring 46 is formed with an externally threaded flange 48 upon which the bezel 49 is screwed. The bezel carries the usual crystal 50 which holds the dial-mat 51 in place upon the dial 5 which in turn rests upon a dial-back 53 which rests upon short studs 54 secured to the front face of the front movement-plate 25 of the removable time-movement. A space 55 between the dial-back 53 and the front movement-plate 25, receives ordinary dial-work comprising a cannon pinion 56 (Fig. 2) driving a dial-wheel 57 carrying a dial-pinion 58 which meshes into and drives the socket-wheel 59. The said dial-wheel 57 is meshed into by a wheel 60 mounted upon the forward end of a short shaft 61 journaled in the movement-plates 24 and 25 and furnished at its rear end with a wheel 62 arranged in position to be meshed into by the pinion 28 mounted on the stud 26 carried by 95 the yoke 19, when the same is swung into its setting position against the tension of the spring 32, by means of the operating-lever 11.

Under normal conditions, my improved 100 keyless clock is ready for winding by the simple rotation of the bezel 49 from left to right, whereby the teeth 41 of the internal gear 42 operate to rotate the winding wheel 29, and hence the arbor 30 upon which the 105 main spring (not shown) within the barrel 37 is wound. To set the clock, the button 8 is seized by the fingers and shoved from left to right, whereby the operating-lever 9 is turned upon the sleeve 12 as upon a fulcrum 110 and its cam surface 17 caused to engage with the arm 18 of the yoke 19 and swing the same against the tension of the spring 32 and thus demesh the pinion 28 from the wheel 29 and cause it to mesh into the wheel 115 62 connected with the dial work of the time-movement and thus rotate the hands. During the operation of setting, the button 8 must be constantly held to the limit of its movement to the right. As soon as this 120 pressure is removed, the spring 32 acts to swing the yoke from left to right whereby the pinion 28 moves from the wheel 62 back into engagement with the wheel 29.

I claim:—

In a rim-winding keyless clock, the combination with a clock-case provided toward its front end with an annular mounting-flange located at a right angle to the axis of the clock case and providing for suspend- 125 130

ing the clock in place from its forward end, of a clock-movement located within the said case, a manually operable rotary winding-and-setting member located at the front end 5 of the said case in front of the said flange, an oscillating winding and setting member connected with the said movement and projecting therefrom outward through the case at a point to the rear of the said flange, and 10 an operating member passing through the

said flange and manually operable from the front thereof, for shifting the position of the said oscillating member.

In testimony whereof, I have signed this specification in the presence of two sub- 15 scribing witnesses.

WILSON E. PORTER.
